SILENT ALARM WRIST WATCH

Franklin A. Raybuck, Philadelphia, Pa.

Application March 10, 1939, Serial No. 260,961

1 Claim. (Cl. 58—16)

My invention relates to a silent alarm wrist watch which is calculated to give a signal to the wearer at the predetermined time it is set for without disturbing others and which at the same time can be made inexpensively and sufficiently compact as not to interfere with the original uses of watches of this character.

Heretofore relatively large alarm clocks have been used which give a rather loud, audible signal and which disturbed other people than the one intended to be awakened or reminded, and furthermore such alarm clocks have been of the standard type or stationary, that is, not of the type which can be conveniently carried about the person. To overcome this difficulty it has been proposed to equip pocket watches with alarms which also give audible signals and which, while not perhaps seriously inconveniencing others, nevertheless betray their presence, which in many instances is not desirable. Furthermore, a pocket watch having an audible alarm signal can be overlooked unless such signal is violent enough to be objectionable.

Doctors, nurses, professional men and in fact all people whose routine requires that they remember to do certain things at certain times need some sort of a convenient and yet effective alarm to serve as a reminder and to that end I have conceived the idea of providing a novel wrist watch which includes a silent alarm which, in addition to vibrating and thus conveying an indirect sensory stimulus, also has means for making direct physical contact with the back of the wrist of the hand, whereby a positive alarm is given to the wearer of the watch without in any way disturbing others or even betraying the presence of the alarm to persons in the immediate vicinity.

To the above ends my invention resides in the combination with a wrist watch of a secondary clock mechanism, a vibrating element having access through the back cover of the wrist watch to the back of the wrist, said vibrating element being adapted to be actuated by said secondary clock mechanism together with means for winding and setting or resetting said secondary clock mechanism in cooperative relation to the primary conventional clock mechanism of the wrist watch.

My invention further relates to certain features of construction by means of which an alarm mechanism is strong enough to be effective and yet can be compactly and inexpensively produced.

Other features of construction and advan-

tage will be more clearly understood from the following specification and the accompanying drawings in which:

Fig. 1 represents a top plan view of a wrist watch embodying my invention.

Fig. 2 represents a diagrammatic top plan view showing certain details of construction.

Fig. 3 represents a diagrammatic bottom plan view showing other details of construction.

Fig. 4 represents a diagrammatic view partly in section and partly in elevation showing details of construction of the watch clock mechanism and the alarm clock mechanism, certain parts being omitted.

Fig. 5 represents a diagrammatic view partly in section and partly in elevation showing certain details of the alarm mechanism and the means for operating it.

Fig. 6 represents a top plan view of the setting hand of the watch embodying my invention.

Fig. 7 represents a bottom plan view of the setting hand shown in Fig. 6.

Fig. 8 represents a top plan view of the conventional hour hand of the wrist watch as the same is modified for use in connection with my invention.

Fig. 9 represents a side elevation of the hour hand shown in Fig. 8.

Referring to the drawings in which like reference characters indicate like parts, and more particularly to Fig. 1, it will be seen that my wrist watch embodies a conventional outer casing 10 which houses the silent alarm mechanism of my invention as well as the conventional clockwork which operates the time piece proper. The casing 10 is provided with the usual opening 12 through which the conventional dial 14 together with the hour hand 16, the minute hand 18 and the alarm-setting hand 20 may be seen. Also, my novel wrist watch is provided with the conventional stem 22 for winding the watch and setting the hands 16 and 18 in the well known manner, and with the auxiliary stem 24, for winding the clock mechanism for operating the alarm and for setting the alarm hand 20.

Referring to Figs. 2 and 3 it will be seen that the stem 22 actuates the cog 26 which also turns the cog 28 to wind the usual spring (not shown) and which, through intermediate conventional gearing (not shown) actuates the shaft 30. The shaft 30 carries the usual cog 31 which carries the hour hand 16 and the minute hand 18, and the special cog wheel 32 which carries the alarm hand 20. The cog 32 and the alarm hand 20 do not turn with the turning of the shaft 30. In

this connection it will be understood that when the stem 22 is pulled out it is disconnected from the cogs 26 and 28 and, through conventional gearing (not shown), it turns the shaft 30 to "set" the hands 16 and 18 without affecting the cogs 26 and 28, which wind the spring of the watch.

The opposite stem 24 through the cogs 36 and 38, winds another spring (not shown) which spring serves for the purpose of actuating the alarm to be hereinafter described. Similarly, and by equally conventional means (not shown), when the stem 24 is pulled outwardly it ceases to affect the cogs 36 and 38 and the spring wound thereby, but acts only on the cog 40 which meshes 15 with the cog 42 to turn the cog 32 carrying the alarm hand 20 to any desired position on the dial and thus set the alarm for any desired time. The cog 32, which carries the alarm hand 20, is provided with an opening 46 which is connected 20 with a gradually tapering cam-like surface or groove 48 of a predetermined length. The cog 31 which carries the hand 16 underlies the cog wheel 32 carrying the alarm hand 20, and is provided with the pin 52, so that, as the cog 31 25 turns around with the shaft 30, the pin 52 will enter the opening 46 and, as the cog 31 turns further, the pin 52 emerges from the opening 46 along the groove or cam surface 48. From this it will be seen that while the cog 32 is spaced from the cog 31 and this condition continues until the pin 52 enters the opening 46 whereupon the cog 32 drops upon the cog 31 for a time predetermined by the relationship of the opening 46 and groove 48 to the 30 pin 52.

It will be noted that all the clockwork mechanism, whether it be of the conventional type or whether it be that which is added to carry out my invention, is enclosed between the upper and lower supporting plates 58 and 60, and from Figs. 2 and 4 it will be seen that to the upper plate 60 is secured at 62 the flat spring 64 the center portion of which rests upon the cog wheel 32 so that the flat spring 64 is raised and lowered by the rise or fall of the cog wheel 32 with respect to the cog 31. Thus, when the cog wheel 32 is riding on the pin 52 the spring element 64 is pushed upwardly as viewed in Fig. 4 and, when 45 the cog wheel 32 temporarily drops upon the cog wheel 31, due to the entry of the pin 52 into the opening 46, the spring 64 is lowered accordingly. As is best seen from the left hand portion of Fig. 4, the flat spring 64 is deflected downwardly 50 as at 66 and horizontally as at 68 to form a brake which engages the brake wheel 70 on the shaft 72. While the flat spring 64 is in its uppermost position as shown in Fig. 4, the brake 68 engaging as it does the brake wheel 70 prevents rotation 55 of the latter as well as rotation of the shaft 72 and vice versa. The shaft 72, in addition to the brake wheel 70, carries the cog 74 which meshes with the cog 76 on the shaft 78 which also carries the cog 80 which meshes with the cog 82 on the shaft 84. The cog 82 meshes with the cog 38 which is actuated by the usual spring (not shown). In this way the spring (not shown) is 60 constantly tending to actuate the shaft 72, except for the constant braking action of the brake shoe 68 of the flat spring 64. Thus, the shaft 72 is held stationary by the brake 68 as long as the cog 32 is riding upon the pin 52 and is spaced from the cog 31. When the pin 52 enters the opening 46 to allow the cog 32 to drop onto the cog 31 the brake 68 is released from the brake wheel 70

and this allows the shaft 72 to turn under pressure of the spring (not shown).

To the under side of the plate 58 is secured as at 88 one or more alarm elements 90 and 92 each of said alarm elements being deflected downwardly and horizontally to terminate in the pins 94. The pins 94 are adapted to pass through the sleeves 96 formed in the bottom 98 of the outer casing 10 of the watch. By reference to Fig. 5 it will be seen that the alarm elements 90 and 10 5 have a range of movement defined by the positions shown in dotted and solid lines in that figure so that, when the alarm elements are in their lowermost position, the pins 94 extend slightly below the level of the outer casing 98, 15 as shown in solid lines, and so that, when the alarms 90 and 92 are in their uppermost position the pins 94 remain within the sleeves 96 as shown in dotted lines in Fig. 5. The shaft 84, which is actuated by the main spring under the 20 cog 38 when the brake 68 is released, has its lower end deflected as at 100 so as to engage the inclined portions of the alarms 90 and 92 in advance of their horizontal extensions so that, as the shaft 84 is rotated, the deflected portion 100 25 thereof, rides on the underside of the inclined portions of the alarm elements 90 and 92 and causes the latter to vibrate in the direction of the arrows in Fig. 5. The vibration of the alarm elements 90 and 92 produces a slight sound which 30 is audible to the wearer and the movement of the pins 94 up and down through the sleeves 96 produces a hammering or tapping action on the wrist of the wearer, which constitutes a positive alarm which cannot be overlooked. 35

The operation is as follows:

Assuming the wearer of the watch desires to wake up at 7:00 o'clock a. m., the alarm hand 20 is moved to the numeral 7 by pulling out the winding stem 24, and of course this must be done 40 some time after 7:00 o'clock p. m. When the hour and minutes hands 16 and 18 have moved around to indicate 7:00 o'clock a. m., the cog 31 carrying the hand 16 has moved through the desired arc and the pin 52 enters the opening 46. 45 This drops the cog 32 down into contact with the cog 31 thus releasing the upward pressure against the spring 64 and permitting the latter to drop, thereby disengaging the brake 68 from the brake wheel 70. This releases the shaft 72 and permits it to turn under tension of the spring which is wound by the cogs 36 and 38, and, when the shaft 72 is free to turn, the cog 74 turns the cog 76 and the cog 80, which in turn meshes with and actuates the cog 82 on the shaft 84. This 50 causes the shaft 84 and the deflected portion 100 thereof to spin about its axis and the bottom portion 100 engaging the inclined portions of the alarm elements 90 and 92 causes the latter to reciprocate vertically so that the pins 94 hammer 60 the wrist of the wearer through the sleeves 96. This goes on until the spring is exhausted or until the wearer awakens and stops the alarm by pulling out the stem 24 and turning the cog 32. When this is done the bevelled top of the pin 52 65 gradually rides out of the opening 46 along the groove or cam surface 48, and, when the pin 52 has cleared the groove 48, the cog 32 is again riding on the pin 52 and is spaced from the cog 31 as shown in Fig. 4. In this position the cog 70 72 pushes the spring 64 upwardly (as viewed in Fig. 4) thus pressing the brake 68 against the wheel 70 and arresting the movement of the shaft 72 and hence of the shaft 84. Due to the gearing used, as well as to the size and disposition of the

spring 84, and the fact that the brake 88 acts on the periphery of the wheel 70 instead of directly upon the shaft 72, very little force is required to retain the wheel 70 and the shaft 72 stationary against the constant urge of the spring wound by the cogs 36 and 38.

Assuming that a wrist watch of my invention is worn by a nurse who must take temperatures or give medicine at ten, fifteen, or thirty minute intervals, it will be seen that the nurse, provided with a positive alarm that assures prompt attention to the specified duties at the specified critical periods, can carry on her work without disturbing the patient, and this also greatly relieves the tension which would be otherwise imposed upon the nurse if she had to keep strict watch over the passage of time. Similarly, a housewife who must baste a roast every so often, or who is baking a cake that must be taken out in exactly twenty minutes, is very likely to overlook the passage of time due to preoccupation with other duties unless she is to drop everything and attend strictly to this one item, which is highly undesirable. These are but two illustrations of the many uses of my novel watch, but it is obvious that everybody in every occupation will have occasion to remember certain things at certain times so that my novel watch has a universal applicability.

Especially important is the fact that my novel alarm is not only silent so as not to disturb others or even betray its presence to others but also that it affords a positive alarm, which cannot be overlooked, by producing a harmless but nevertheless effective tapping or hammering on the sensitive skin of the wrist. While I have shown two alarm elements 98 and 92 it is obvious that

only one of the elements can be used if desired. The sleeves 96 constitute a relatively tight fit around the pins 84 so as to prevent ingress of dirt and dust while at the same time permitting free movement of the pins 84. Furthermore, the 5 clockwork proper is all disposed above the plate 58 and the sleeves 96 through which the pins 84 project are provided in the bottom 98 of the outer casing 10 as best seen in Fig. 5.

Having thus described my invention, what I 10 claim as new and desire to secure by Letters Patent is:

A silent alarm wrist watch comprising a primary clock mechanism for actuating the hands of said watch, a secondary clock mechanism for 15 operating an alarm element, a brake element normally holding said secondary mechanism inoperative, said brake element being adapted to be released at predetermined times by said primary mechanism, a vertically disposed shaft adapted 20 to be rotated by said secondary clock mechanism when said brake is released, the lower end of said shaft being deflected to form an angular extension, and a spring alarm element comprising an inclined portion extending across and above 25 the plane of rotation of said angular extension and a vertical portion normally in contact with the wrist of the wearer through an opening in the back of the wrist watch casing, said vertical portion being lifted from contact with the wrist 30 of the wearer by the rotation of said shaft and the intermittent engagement of said angular extension with the underside of the inclined portion of said alarm element.

35

FRANKLIN A. RAYBUCK.
